JAMES NAYLOR, OF ARLINGTON, NEW JERSEY.

MOTOR.

1,323,542.

Specification of Letters Patent.

Patented Dec. 2, 1919.

Application filed October 19, 1915. Serial No. 56,718.

To all whom it may concern:

Be it known that I, JAMES NAYLOR, a citizen of the United States, residing at Arlington, in the county of Hudson and State 5 of New Jersey, have invented a new and useful Motor, of which the following is a specification.

My improvements relate to that class of motors generally known as "turbines," in 10 which the velocity of expanding steam or the explosive effect of a gas is communicated directly to a rotor for useful work.

The object is to make a stronger, safer and cheaper unit, and one that will have a much 15 wider scope of adaptation to existing installations than do the turbines now made.

The invention consists of the construction and its operation in such manner that the objective features as stated are attained primarily by the elimination of all keys, bolts 20 and rivets from the rotor so common in all machines of this class.

In the drawings, Figure 1 is a side elevation shown in section on the center line 25 transversely; Fig. 2 is a plan in part-section; Figs. 3, 4, 5 and 6 are details, and Fig. 7 a modification of Fig. 1.

The flow of steam, gas or air through this 30 motor is through rectangular nozzles inserted into openings on the opposite sides, the direction being at an angle of about forty-five degrees above and below the horizontal center or axial line.

A is the bed plate upon which the motor 35 is mounted.

B is the cylindrical part, or body, of the case or container open at its ends and provided with inlet and outlet openings on opposite sides. The ends are flanged and a 40 common provision is made to secure same to the bed plate.

The heads C are provided with the ordinary stuffing boxes and glands, and are bolted to the part B.

45 The parts B and C together may be termed the "container," meaning that it contains the rotor.

The pedestal bearing boxes D are bolted to the bed plate A and serve to freely hold 50 the rotor to its container in running alignment with the finished surfaces on the inside.

The inlet fittings E are alike, each being reversible, and provided with double openings from the outside with a flange to cover

the one not used, and a rectangular opening which is the nozzle.

These nozzles e are both on the horizontal center line of the motor with one edge exactly upon it; this is for the purpose of having the rotor run in either direction when it is installed. It is apparent that after an installation is made the parts E E may be taken off and replaced upside down and all joints to piping and motor re-made so that a 60 reversion of motion is the result in Fig. 1.

The outlets F are the connecting means to the condenser and to the atmosphere, and are located midway of the inlets when the motor is intended to be reversible when running, as is shown in Fig. 7; when not reversible the direction of outlets may be at any angle, from the horizontal as seen in Fig. 1 to the vertical in Fig. 7 but always directly opposite to each other on a line 65 through the axis of the rotor.

With this construction it is seen that friction will be at the minimum by the balanced effect of the forces upon the rotor and that the pipe connections can easily be made. 70

G is the arbor upon which the hub H is mounted by means of a right-hand screw thread h, the solid collar h' and the lock nut h'' having a left hand screw thread to tighten against the said hub. 75

These parts constitute a mandrel upon which the other revolving parts are carried. The said hub is provided with a solid or integral collar I at one end, the four integral longitudinal projections J which are 80 termed "feathers" and the removable collar K which has a right hand screw thread to engage a corresponding one upon the hub.

The four equi-distant feathers on the hub are essential to carry the intervening rings 85 and the four notches in the thin pressed disks are necessary to fit the said feathers.

The parts to be mounted upon the hub consist of two extra-heavy disks L smooth on their true surfaces, both alike with the exception of the bore, the one being larger than the other, a number of disks M and the intervening rings N. These rings are mounted upon the four feathers of the hub and are thus centered to the axis of the rotor 100 creating the zig-zag spaces between the disks M. When the size of the motor is 105 considered modifications of this ring must be used, one being shown at Fig. 5. It is imperative that these rings be perfectly true 110

on the face surfaces, the said surfaces are reduced by the outstanding annular surfaces of which three on each side are shown, two opposite each other at the periphery and two at the bore with the others midway between. One of the disks M is shown in face view at Fig. 3. They are made of thin homogeneous steel plate pressed into form; before pressing, the periphery is made to a sharp edge, with a central opening to fit the feathers of the hub. Each disk has a series of inclined flat surfaces obtuse to each other as seen in Fig. 4 and radial as shown in Fig. 3. Two opposite ridges m m are in line with two opposite notches of the central opening on the horizontal axial center line and two valleys m' m' in line with the other two notches on the vertical axial center line; this order makes possible the interlocking to position of the thin disks upon the feathers and hub.

When all these parts are together and tightened up by the collar K there is presented a rotor complete, having a series of zig-zag spaces as is shown in plan view full size in Fig. 4 for four inclinations.

The inclination of the deflecting surfaces to the plane of rotation is shown as twelve degrees and the width circumferentially three degrees or equal to six for each corrugation, one half the surface is used for deflection in running clockwise and the other half for reverse.

As every space between the disks M has an obverse and reverse face and the apexes of the ridges m of the said disks in each space are on the same plane of rotation, it is impossible for the streams to project on straight lines; the result is that impact, friction and reaction take place all in the direction of motion. In making the disks degrees are used for dividing the circle, the notches in the central opening are ninety apart and fifteen inclinations equal the same space, as shown in Fig. 3; the ridges at m m are on the horizontal center line and the valleys m' m' on the vertical center line, this order being reversed on the reverse face and on assembly the result is seen in Fig. 4.

Gear or belt connection is made to the arbor at O and for any auxiliary or governor at o.

In operation the steam, gas or air is projected in lines over areas or deflectors for a quarter of a revolution in passing through the rotor.

The stream is divided on entering the motor at opposite sides and after passing the nozzles is sub-divided into many separate streams by the knife edges of the disks, each of which passes between two of the said disks M, the whole uniting at the clearing of the rotor at the exhaust outlets.

The heavy disks at the outside of the series of disks and rings are to prevent any

lateral expansion of the stream and thus force it forward in the direction of rotation. The inner faces of the said disks are on two different planes of rotation, the one for contact with and the other for clearance of the disks M. The nozzle lines being directed to the outlets allows the influence of draft to accelerate the velocity.

It has been described how this motor may be constructed of the same parts to run in either direction; by reference to the modifications shown in Fig. 7 it will be seen how the same rotor is made reversible while running. The motor is substantially the same, oscillating nozzles being shown for the purpose of reversion. These nozzles P, P are also shown at Fig. 6. Q is the rectangular adjudicate opening, R the stem by which it is moved with the lever S and tie connection T. The full lines of this connection is the position when the direction is as shown by the arrow and when moved to the dotted position the motion of the rotor will be reversed.

It may here be observed that the inlet openings into the container are centrally on the horizontal axial line above and below alike, the whole of said opening being taken by the nozzles in reversing or opposite positions in the same direction of rotation.

When it is required that the motor shall run under governor control the nozzles P are used as cut-offs and the tie connection operated directly from a governor and then the direction of rotor must be either one way or the other.

In many reversals of motion full speed is not desired, therefore a modified and efficient construction may have the inlet e at one side and the inlet P at the other for this and other economical reasons.

Especial attention is called to the fact that in the operation the initial velocity of the stream becomes gradually but quickly reduced within the rotor coincident with the expansion occurring therein also, the latter tending to accelerate the velocity and while this may seem paradoxical the whole force is forward even with all its frictional contact upon the revolving parts of the rotor and not upon any stationary part. As condensation is rapidly taking place as the lower pressures are reached, it is obvious that the slower the speed of the rotor the less will be the bad effect of the condensate.

I am aware that in rotors of this type a series of spaces between surfaces is not new, instances being of flat disks and disks with curved faces, also of abrupt faces upon a cylinder, such I do not claim but having described and clearly shown the difference in the new and the improvement over the old I claim—

1. In a motor the combination with a container having bearings each side and provided with rectangular and reversible inlet

- nozzles directly upon the horizontal axial center line of said container and opposite openings for exhaust; of a rotor provided with means to receive and securely hold a 5 series of thin pressed disks, each of which has a round central opening with four equidistant notches as shown and described.
2. In a motor the combination with a container having opposite openings for inlets 10 centrally on the horizontal axial line, bearings apart from said container and exhaust openings above and below the said line; of a rotor provided with means to receive a series of alternate thin pressed disks and 15 intervening rings all locked in their regular order and loosely in place prior to the final tightening and means therefor consisting of separate screw threaded collars upon separate screw threads of different diameters.
- 20 3. In a motor the combination with a container having openings for inlets and exhausts on opposite sides, an arbor and bearings to receive the arbor; of a hub mounted thereon and secured by right and 25 left hand screw-threads, the said hub to receive the elementary parts of said rotor in an interlocking manner so that the ridges of the pressed disks adjacent to each other are in the same plane of rotation and oppo- 30 site laterally to the valleys thereof and means consisting of an external screw thread upon the said hub and a collar provided with corresponding internal screw thread for engagement to make same secure 35 as a whole prior to mounting on said arbor.
4. In a motor the combination with a container having opposite openings centrally on the horizontal axial line for inlets, outer bearings and openings for ex- 40 haust above and below the said line; of a rotor composed of an arbor having a collar and right and left hand screw threads thereon to receive a hub, said hub having a collar and four feathers integral therewith 45 to form a mandrel, a series of disks and rings mounted thereon, a separate means for securing the said hub to said arbor and said disks and rings to said mandrel each consist- 50 ing of a threaded annular collar.
5. In a motor the combination with a rotor composed of an arbor, a hub provided with four equidistant feathers secured thereto to form a mandrel, a series of thin pressed disks and intervening rings mounted 55 thereon to different diameters centrally to the said arbor, the four feathers of said hub reaching through same and means for securing all the parts mounted thereon to the said hub so as to be removable from the 60 said arbor without any loosening of the said disks; of a container with outer bearings and openings for inlet and exhaust.
6. In a motor the combination with a container having opposite rectangular openings 65 on the horizontal axial center line, rectangu-
- lar nozzles inserted into same for inlets and exhaust openings above and below the said line on opposite sides; of a mounted rotor provided with a series of pressed sharp edged disks, intervening rings and the heavy 70 disks outside the said series.
7. In a motor the combination with a container having rectangular inlets, exhaust outlets and bearings all on opposite sides; of a rotor comprising a mandrel with means 75 to receive heavy outside disks, the inner surfaces of which are on two different planes of rotation, a series of alternate disks and rings being between the same and in tight contact with the innermost surfaces thereof, 80 the other faces clearing the ridges of the thin disks in proximity thereto and to coincide in width with the said rectangular inlets.
8. In a motor the combination with a 85 mounted rotor comprising a series of alternate pressed disks and rings with heavy outer disks having their inner faces on different planes of rotation and a means for locking the said disks to position and for 90 tightening; of a container with rectangular and reversible inlets on opposite sides directly upon the horizontal axial center line of said rotor and opposite exhausts.
9. In a motor the combination with a 95 mounted rotor composed of a series of outstanding sharp-edged disks the ridges of which and those adjacent being on the same plane of rotation throughout the said series and supported laterally by heavy disks and 100 intervening rings; of a container provided with outer bearings, rectangular and reversible inlets coinciding in width to the space between the said heavy disks and exhaust openings on opposite sides.
10. In a motor the combination with a container having means to mount a rotor and provided with inlets and outlets all on opposite sides; of a rotor composed of its elementary parts and means consisting of 105 right and left hand screw threads and a collar upon the arbor with screw threads of the hub and collar whereby it is readily detachable as a whole from its arbor and so replaced.
11. In a motor the combination with a container having means to mount a rotor and provided with inlets and outlets all on opposite sides; of a rotor composed of parts which are all annular in form, and having 110 a positive means consisting of a removable hub provided with an integral outstanding collar, four integral equi-distant feathers, screw threads and threaded collar to engage same for holding same in alinement and 115 order prior to the final tightening.
